UNITED STATES PATENT OFFICE.

BURNHAM C. STICKNEY, OF ELIZABETH, NEW JERSEY, ASSIGNOR TO UNION TYPEWRITER COMPANY, OF JERSEY CITY, NEW JERSEY, A CORPORATION OF NEW JERSEY.

TYPE-WRITING MACHINE.

No. 810,359.

Specification of Letters Patent.

Patented Jan. 16, 1906.

Application filed April 6, 1903. Serial No. 151,335.

To all whom it may concern:

Be it known that I, BURNHAM C. STICKNEY, a citizen of the United States, and a resident of Elizabeth, in the county of Union and State of New Jersey, have invented certain new and useful Improvements in Type-Writing Machines, of which the following is a specification.

This invention relates to the key-actions of writing-machines, and especially to those in which the type-bars strike rearwardly against a platen; and its object is to improve the touch of the keys and to simplify the construction and operation of the key-actions.

My invention consists in certain combinations of devices and features of construction, which will be hereinafter fully set forth, and particularly pointed out in the concluding claims.

In the drawings forming part of this specification, Figure 1 is a central longitudinal vertical section of a full keyboard front-strike pad-machine constructed in accordance with my present improvements, the parts being shown in normal position. Fig. 2 is a view of the preferred form of key-lever. Fig. 3 is a view of the type-action seen at Fig. 1, but with the parts shown in printing position. Fig. 4 is a sectional front elevation of the machine, showing the type-actions.

In the several views like signs denote like parts.

The framework of the machine may include a rectangular base 1, corner-post 2 thereon, and a top plate 3, over which may run a carriage having a platen 4. Against the front side of the platen may strike a series of types, of which one is shown at 5 as normally resting upon a segmental inking-pad 6, supported at its ends upon the top plate. Said type is mounted upon the rear end of a bent carrier 7, pivoted at its end at 8 upon the free end of a lever 9, and also pivoted at its front end at 10 upon an idle link 11 in such a manner that when operated the type follows the dotted path 12 at Fig. 3 from the pad to the platen. The type-carriers, the levers 9, and the links 11 are all radially disposed, the levers 9 being mounted upon a curved fulcrum-rod 13, fixed upon a segment 14, which is radially slotted at 15 to receive the lever-hubs, and the links 11, working upon a curved rod 16, supported upon a segment 17, which is

radially slotted at 18 to receive the links, said segments being supported at their ends 55 upon the top plate. My improvements may also be applied to other forms of type-bars, including those which work upon single pivots and print through a ribbon. The key-levers are T-shaped and comprise forwardly-extending portions or arms 19, bearing at their forward ends keys 20, upwardly-extending arms 21 at the rear ends of the arms 19 and downwardly-extending arms 22, forming continuations of the arms 21. Pull-links 23 are pivoted at their rear ends at 24 to the type-levers 9 and extend forwardly to the key-lever arms 21, to which they are pivoted at 25. The downwardly-extending key-lever arms 22 have elongated curved treads or rockers 26, which are adapted to have a rocker motion upon a plate or other suitable elongated fulcrum or bearing 27, which is arranged vertically or on edge and extends transversely in rear of the arms 22 and is supported upon the opposite walls of the base 1. The key-levers at their cross-arm portions are provided with notches 28, which engage a transverse horizontal bar 29, fixed at its ends to the side walls of the base, whereby vertical displacement of the rear ends of the levers is prevented. A comb 30 for guiding the lower ends of the arms 22 may be suitably mounted in the base, the forwardly-extending portions of the levers being guided by the usual comb 31. The rod 29 prevents the rear end of each of the levers from moving downwardly, so that when a key is depressed the entire lever tends to swing or rock upon the vertical plate 27, 90 whereby the arm 21 is vibrated forwardly, and through the link 23 the type-bar is pulled up to print, as illustrated at Fig. 3. Upon the release of the key from pressure the parts return to normal position partly by gravity and partly by the aid of a draw-spring 32, the forward end whereof is attached to the link 23 and the rear end whereof is caught upon a hook 33, provided upon the curved frame of the pad 6. It will be noted that the point 25 has a forward and backward movement. By reason of the rocker action of the arm 22 upon the plate 27 the leverage or purchase of the key upon the type-bar, which leverage is so great at the initial part of the stroke as to avoid jar to the

finger of the operator, gradually decreases until the stroke is completed, the effect being not only to soften the key touch, but also to increase the speed of the type as it nears the platen, so that it may deliver a powerful blow upon the paper placed thereon.

It will be seen that I have provided a connection between the key-lever and the type-bar and that by the described means the latter is started slowly in motion, which is a matter of considerable importance especially in machines having compound type-bars, which are usually heavier than simple type-bars and are proportionately harder to set in motion and more resisting to the key touch.

At Fig. 3 it will be seen that the key-lever is equivalent to a simple bell-crank or elbow-lever, the power being applied to the key, the fulcrum being at the point of contact of the lower end of the rocker 22 with the fulcrum-plate 27 and the load-point being at 25, these three points being at the apexs of a triangle. It will be noted that when the parts are in the Fig. 3 position or at the completion of the stroke the leverage of the key upon the type-bar is the least.

At Fig. 4 it will be noted that the key-lever arms 21 are shortest in the middle of the system, but are progressively longer from the middle to the sides of the system to conform to the gradually-increasing heights at which the type-bars are mounted. It will also be noted that the downwardly-extending arms 22 of the key-levers are longest at the middle of the system and grow progressively shorter toward the sides of the system, thereby to compensate for the increased length of the upwardly-extending arms and to render the dip of the keys more nearly uniform.

In the preferred form of the invention (shown at Fig. 2) the cross-arms of the key-levers are supported at the point of least vibration of the levers or between the ends of the arms 22, at which point there are formed in the levers suitable notches 34, which engage a horizontal bar 35, fixed upon the plate 27.

Variations may be made within the scope of my invention, and portions of my improvements may be used without others.

Certain of the features herein shown and described are claimed, broadly, in my applications Serial Nos. 151,334 and 151,336, filed of even date herewith.

What I claim as new, and desire to secure by Letters Patent, is—

1. In a front-strike writing-machine, the combination of a series of rearwardly-striking type-bars; a series of key-bearing bell-crank connected thereto; said bell-cranks comprising forwardly-extending key-bearing arms and downwardly-extending arms having elongated treads, and the points of said levers which are connected to said type-bars having a forward and backward movement;

a fulcrum-plate upon which said treads have a rocker motion; said fulcrum-plate standing on edge; and a bar engaged by all of said treads for supporting the same against downward or upward displacement.

2. In a front-strike writing-machine, the combination of a series of rearwardly-striking type-bars; a series of levers connected to said type-bars and comprising forwardly-extending key-bearing arms and downwardly-extending arms having elongated curved treads, notches in the latter arms, a fixed transverse supporting-bar engaged by said notches, and an upright plate upon which said treads have a rocker motion.

3. In a front-strike writing-machine, the combination of a series of rearwardly-striking type-bars; a series of T-shaped levers comprising forwardly-extending key-bearing arms, upwardly-extending arms, and downwardly-extending arms having elongated treads; links extending forwardly between said type-bars and said upwardly-extending arms; notches in said levers; a fixed transverse bar engaged by said notches for preventing upward or downward displacement of said levers at their rear ends; and a fulcrum-plate upon which said downwardly-extending arms have a rocker motion.

4. In a front-strike writing-machine, the combination of a series of rearwardly-striking type-bars; a series of T-shaped levers comprising forwardly-extending key-bearing arms, upwardly-extending arms, and downwardly-extending arms having elongated treads; links extending forwardly between said type-bars and said upwardly-extending arms; notches in said downwardly-extending arms; a fulcrum-plate upon which the latter arms have a rocker motion; and a fixed transverse bar mounted upon said plate between the upper and lower edges thereof and engaged by said notches for preventing upward or downward displacement of said levers at their rear ends.

5. In a front-strike writing-machine, the combination of a series of rearwardly-striking type-bars; a series of T-shaped levers comprising forwardly-extending key-bearing arms, upwardly-extending arms, and downwardly-extending arms having elongated treads; links extending forwardly between said type-bars and said upwardly-extending arms; notches in said levers; a fixed transverse bar engaged by said notches for preventing upward or downward displacement of said levers at their rear ends; a fulcrum-plate upon which said downwardly-extending arms have a rocker motion; and returning-springs attached to said links and extending to a fixed support.

6. In a front-strike writing-machine, the combination of a system of rearwardly-striking type-bars; a system of levers comprising forwardly-extending key-bearing arms,

downwardly-extending arms having elongated treads, and upwardly-extending arms connected to the type-bars; and a bearing-plate upon which said treads have a rocker motion; said upwardly-extending arms being shortest at the middle of the system and being progressively longer from the middle to the sides of the system, and said downwardly-extending arms being longest at the middle of the system and being progressively shorter from the middle to the sides of the system.

7. In a front-strike writing-machine, the combination of a system of rearwardly-striking type-bars, a system of levers comprising forwardly-extending key-bearing arms, downwardly-extending arms having elongated treads, and upwardly-extending arms, a bearing-plate upon which said treads have a rocker motion; said upwardly-extending arms being shortest at the middle of the system and being progressively longer from the middle to the sides of the system, and said downwardly-extending arms being longest at the middle of the system and being progressively shorter from the middle to the sides of the system; links extending forwardly between said type-bars and said upwardly-extending arms; returning-springs attached to said links; and means for preventing upward or downward displacement of said downwardly-extending arms.

8. In a front-strike writing-machine, the combination of a series of radial links, a series of rearwardly-striking type-carriers pivoted upon the free ends of said links; a second series of radial links upon which said type-carriers are also pivoted; a series of T-levers comprising forwardly-extending key-bearing arms, upwardly-extending arms, and downwardly-extending arms; connections extending forwardly between one of said sets of radial links and said upwardly-extending arms; elongated treads formed on said downwardly-extending arms; a plate upon which said treads have a rocker motion; and a transverse bar for supporting the rear ends of said levers.

9. In a front-strike writing-machine, the combination of a series of rearwardly-striking type-bars; a series of T-shaped levers comprising forwardly-extending key-bearing arms, upwardly-extending arms, and downwardly-extending arms having elongated treads; links extending forwardly between said type-bars and said upwardly-extending arms; notches in said downwardly-extending arms; a fulcrum-plate upon which the latter arms have a rocker motion; and a fixed transverse bar mounted upon said plate between the upper and lower edges thereof and engaged by said notches for preventing upward or downward displacement of said levers at

their rear ends; said forwardly-extending arms being attached to said cross-arms at points above said notches.

65

10. In a front-strike writing-machine, the combination of a series of rearwardly-striking type-bars, a series of key-bearing levers, a series of links connecting said type-bars to said levers; said levers having a series of upwardly-extending arms to whose upper ends said links are attached, said arms being shortest at the middle of the system, and increasing progressively in length from the middle to the sides of the system, and means for affording a change of fulcrum of said levers as they are depressed.

70

11. The combination with a series of type-bars of a series of T-shaped key-levers, a link connecting each type-bar to one arm of one of said levers, a key carried by another arm of said levers, said levers also having at their rear ends downwardly-extending arms provided with suitable bearings; said downwardly-extending arms being longest at the middle of the system and decreasing progressively in length from the middle to the sides of the system, and a coöperating bearing for the downwardly-extending arms of said levers.

80

12. In a type-writing machine, the combination of a front-strike jointed type-bar, and a key-lever operatively connected to said type-bar, said key-lever having a downwardly-extending arm and a bearing on which said arm rocks and changes its fulcrum.

95

13. In a type-writing machine, the combination of a series of segmentally-arranged type-bars, key-levers operatively connected thereto and having rocker-arms that afford a change of leverage as the key-levers are depressed, the rocker-arms at the center of the system having a greater extent of rocking movement on their bearings than those at the sides of the system.

100

14. In a type-writing machine, the combination of a series of segmentally-arranged type-bars, key-levers having connecting-arms of different lengths operatively connected to the type-bars and having rocker-arms that afford a change of leverage as the key-levers are depressed, the rocker-arms for the key-levers with the shorter connecting-arms having greater extents of rocking movement on their bearings than the rocker-arms for the key-levers having the longer connecting-arms.

105

Signed at the borough of Manhattan, city of New York, in the county of New York and State of New York, this 31st day of March, A. D. 1903.
